UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

ELECTRIC SWITCH.

1,307,818.

Specification of Letters Patent. Patented June 24, 1919.

Application filed February 5, 1916. Serial No. 76,249.

To all whom it may concern:

Be it known that I, GEORGE A. BURNHAM, a citizen of the United States, residing at Saugus, in the county of Essex and State of

5 Massachusetts, have invented an Improvement in Electric Switches, of which the following is a specification.

When electric-switches or circuit-breakers are placed out of doors, as for instance on 10 poles, great care must be taken to prevent the rain and snow from entering the inclosing-case or drifting thereinto by the force of the wind.

This invention has for its object the construction of an electric-switch or circuit-breaker having an inclosing-case especially well adapted to be placed out of doors and to be subjected to the condition of weather above noted.

20 The component parts of the case are fitted together with tight weatherproof joints; the top part of the case overhangs the oil-compartment; the insulated bushings for the circuit-wires are arranged in the bottom of the 25 overhanging portion and extend in a downward direction; the cover of the case is separately removable; the switch elements are arranged on a supporting-plate which is connected with the top part of the case, so that 30 they may be removed as a unit from the case upon removal of the cover; the oil-can is also separately removable from the top part of the case; the overhanging top part of the case has a hollow extension arranged 35 at one side which is open at its lower end and extends over the handle thereby shields the opening in the case from the weather, or, at least, its inner end-portion, so that an externally disposed handle may be employed 40 which is extended through a hole in the wall of the case and is connected with the switch-operating mechanism.

It is also desirable that the switch be in open circuit condition before it is removed 45 from the casing.

Consequently, another object of the invention is in the provision of means whereby the switch can be removed from the casing only when it has been first moved to open 50 position.

This result is obtained by providing the switch operating handle detachable from the switch operating mechanism and extending

it through an opening in the case for engagement with a component part of the operating mechanism. The handle bears a spline which engages a spline way in said component part of the operating mechanism and the opening in the casing has a way permitting the passage of the spline therethrough. The way in the opening through the wall of the casing and the spline way in the component part of the operating mechanism is arranged to be in alinement only in the open condition of the switch, in which condition the handle may be extracted and the switch unit removed from the casing.

At all other positions of the switch mechanism, the ways are not in alinement and upon the attempted removal of the handle the spline is brought up against the solid casing wall which prevents further movement toward the removal of the handle. When the handle is extended through the wall of the casing and is in engagement with the switch mechanism, it effectually locks the switch unit against removal from the casing.

Another feature of the invention is the construction of the switch-operating mechanism which may be easily and cheaply manufactured, is strong and durable and not liable to get out of order, and which may be easily operated.

Another feature of the invention is the construction of the switch elements, both the stationary and the movable switch-elements involving improvements aiming to increase the durability of the parts and also the efficiency of operation, and, furthermore, to enable certain wearing parts to be easily replaced.

Many features disclosed, but not claimed in this application, are disclosed and claimed in application Serial No. 76,248, filed February 5, 1916.

Figure 1 is a front elevation and partial section of an electric switch or circuit-breaker embodying this invention.

Fig. 2 is a transverse vertical section of the same.

Fig. 3 is a side elevation of the switch operating mechanism.

Fig. 4 is a fragmentary detail of a portion of the switch-operating mechanism.

Fig. 5 is a longitudinal vertical section of

one of the stationary switch elements, and a fragmentary portion of a movable switch-element in engagement therewith.

10 represents the oil-can or receptacle which is of any suitable shape and dimensions; 12 is an enlarged top-portion arranged on said can and removably attached thereto by means whereby a water-tight joint is insured; and 13 is a cover fitted on top of said enlarged top-portion by means whereby a water-tight joint is insured. These several components form the inclosing-case.

In the particular structure here shown the enlarged top-portion 12 has a downwardly extended flange 14, fitted to the top of the can which is secured in place by an angularly formed screw 16, with a butterfly nut thereon, which admits of the top-portion and the can being separable. The cover 13 has outwardly extended ears, and bolts 17 pivoted at 18 to the outside of said top-portion, are arranged in detachable engagement with said ears, there being butterfly nuts arranged on said bolts, thus admitting of the removal of the cover. The enlarged top-portion of the case being much larger in area than the can enables it to overhang the can, and the bushings 19, for the circuit-wires, are arranged in the bottom part of said top-portion and extended downwardly so that water flowing down the outside wall of the top-portion will pass the bushings without tendency to enter the case. Said top-portion has, at opposite sides, slotted wings 20, by which the device may be secured to a pole or other support.

The switch-elements are supported by a plate 22, arranged in the top-portion, its margins being secured to the bottom wall thereof by screws or other means, this admits of the switch-elements being removed as a unit upon removal of the cover, or the removal of the top-portion when the latter is separated from the can, and also admits of the removal of the can when the latter is separated from the top-portion.

There are or may be several pairs of stationary switch-elements and corresponding movable switch-elements. In Fig. 5, one of the stationary switch-elements is shown, and it will be understood that the other switch-elements may be similarly constructed. Said switch-element comprises two cylindrical bushings 25 and 26, complementally arranged in alinement, and a long bolt 27 extended through them and projected therefrom at each end, a newly formed pole-piece arranged on said bolt at one end of the element, and newly formed binding-means arranged on said bolt at the other end thereof, the pole-piece and the binding-means, together with the bushings, all being held assembled by the bolt.

The newly formed pole-piece comprises

a flat disk 29, having a center hole for the bolt, and having a metallic clip 30 extended over and detachably secured by a screw 31, to its margin, said clip being coextensive only with the short arc of the disk. 70

A segmental plate 28 or washer also may be employed which is arranged between the disk 29 and the end of the bushing 25. The outer surface of the flat disk 29 is adapted for engagement with the brush 40 of the movable switch-member and a metallic clip 30 is adapted for engagement with the auxiliary contact-member 41 of said movable switch-element, and it will be particularly noted that not only is a good contact insured, 80 but the metallic clip which is subject to the greatest wear, may be reversed, so as to present its both faces for engagement, and may be replaced easily by a new clip.

The binding-means at the top of the bushing 26 comprises a plurality of metal disks or washers 35, superimposed on the other end-portion of the bolt, and nuts 36 arranged on the bolt. Said binding-means also includes a terminal connection for a circuit-wire, which, as here shown, consists of a socketed body-piece 38, adapted to receive the end of the circuit-wire, and a perforated arm 39 formed integral therewith and adapted to be arranged on the bolt, between the nuts and washers, and to be held in fixed position by the nuts when they are turned down tightly on the bolt. The socketed body-piece is arranged at an angle with respect to its supporting-plate, so that the circuit-wire held by it may be directed toward the bushing. 95 100

An insulating housing 71 is arranged over the binding means at the top of bushing 26 for the purpose of protecting said means 105 from oil and spray that at times may be present in the chamber in which the terminals are disposed. Said housing is provided with a cylindrical inner portion 72 adapted to fit over the binding means, and 110 be held thereby against lateral displacement and removable in only a vertical direction. The walls of housing 71 surround the opening therein for the circuit wire or switch lead which extends about said wire for a 115 sufficient distance to completely protect the terminal thereof from oil spray. *

The movable switch-member comprises a brush 40, and an auxiliary contact-member 41, both arranged on a rod 45. The upper 120 end of the rod 45 is connected to a bar 46, which bar may have several rods, as 45, connected with it, so that they are all adapted for simultaneous movement. The bar 46 has an ear 47 to which one end of a link 48 is 125 pivotally connected, the other end of said link being pivotally connected to an ear 50 rising from the supporting-plate. Said link consists of a pair of bars arranged in parallel relation and spaced apart. The means 130

employed for moving said bar 46 thereby to move the switch-elements borne by it is connected with said link 48. As here shown, the toggle is provided for moving the link 48, which is adapted to be operated by the handle which is connected therewith. Said toggle consists of an upper member comprising a pair of flat bars 55, arranged in parallel relation and spaced apart, the upper ends of said bars being connected together by a pin 56, and the lower ends thereof being connected together by a pin 57.

There is a stirrup 58 arranged at the upper end of said upper member which is held in place by the pin 56, and which extends beneath the pin 58, arranged on the link at a point intermediate its length, see Fig. 4, said pin being thus embraced by the stirrup 58 and pin 56. The upper end of the upper member of the toggle is thus loosely connected with the link. The lower member of the toggle consists of an arm 60 extended radially from a hub 61, having its bearings in a hole formed in the ear 50, on the supporting-plate, and said arm 60 is pivotally connected with the lower end of the upper toggle member by a pin 57. The hub has a center-hole 62, with a key-way 63, and said hole is arranged opposite a hole 64 in the wall of the inclosing-case which has a corresponding way 63^a, so that the end-portion 65 of the handle 66, may be projected through said hole in the wall of the case and into the center hole of the hub, thus connecting it with the hub, and by reason of a spline 67 being formed on the end-portion of the handle which enters the key-way, said hub way be oscillated by the handle, thus to operate the toggle and move the link 48, to in turn raise and lower the movable switch-member. The handle, which, as here shown, is a crank handle, is thus externally exposed on the case, and it is protected from the weather, in part at least, by an extension 70 arranged on the outer wall of the case, which is made hollow and extends over the upper end-portion of the handle. The key ways 63 and 63^a in the hub and wall are arranged to be in alinement in the open condition of the switch and the end portion of the handle may thereby enter the casing and engage the hub to close the switch. If an attempt is made to remove the handle with the switch in closed position, the end of said spline is brought into engagement with the solid wall of the casing and further movement is prevented. It is only when the switch is in open position that the spline registers with the way 63^a and the handle may be removed. In all other positions the handle effectively locks the switch unit against removal from the case.

By extending over the end portion of the handle and adjacent thereto, it effectually prevents the removal of said handle from

the case, as the handle must be moved laterally for the disengagement of its shaft or end portion 65 from the switch mechanism and casing and this movement is permitted only when the cover 13 is removed from 70 the casing.

I claim:

1. In an electric switch, an inclosing case comprising a top portion, and a cover for said top portion, a switch unit arranged 75 within said case, a switch operating member having a handle engageable portion having an opening therein adjacent a wall of said top-portion, said top-portion having an opening therein in alinement with the 80 opening in said switch operating member, a crank handle extended through said opening and detachably engaging said switch operating member for the operation of the switch, and said cover having an extension 85 projecting over and shielding the opening in said top-portion from the weather and normally preventing the removal of said detachable handle.

2. In an electric switch, a supporting 90 plate, a stationary switch member supported thereby including insulating bushings having complementary end portions arranged in alinement and between which said supporting plate is clamped, one of said bushings extended through and above said supporting plate for a considerable distance to provide a long leakage path between a conductor extended through said bushings and said supporting plate, a bolt comprising a 100 conductor extended through said bushings and terminating in a head, a contact block comprising a flat plate detachably and reversibly arranged on said bolt and presenting a smooth contact surface to a movable 105 switch member, a U shaped supplemental contact block arranged over a part of the periphery of said plate and detachably secured thereto, said block being reversible to present a fresh contact face to a movable 110 switch member, said contact block projecting above the surface of said plate whereby initial contact with a movable switch member is made, said bolt being threaded at its upper end and a nut arranged thereon to 115 clamp said detachable contact block, bushings and supporting plate together, and means arranged on said upper end for connection with a switch lead.

3. In an electric-switch, a switch-operating mechanism comprising a bar supporting a movable switch-member, a link loosely connected at one end with said bar and pivotally connected at its other end, said bar and movable switch member being otherwise unguided, a stirrup pivotally connected with said bar, a toggle, the upper member of which is loosely connected with said stirrup and its lower member adapted to receive a handle. 120 125 130

4. In an electric switch, an inclosing case, switch elements, and operating mechanism in said case and supported by a component part thereof, said switch operating mechanism including a guide link connected with the movable switch member to guide its movements, the movable switch member being otherwise unguided, a stirrup pivotally connected with said link and a toggle, one member of which is connected by a link to said stirrup and the other member of which consists of an arm extended radially from a hub having a center-hole, and a crank handle arranged outside of the case and having an end portion which normally extends through a hole in the wall of the case and enters the center-hole of the hub.
5. In an oil switch, a supporting plate, a stationary switch member arranged thereon having binding means for connection with a switch lead, and an insulating housing detachably arranged over said binding means to protect said means and terminal from oil or spray, having a portion thereof shaped to conform to said binding means whereby said housing is maintained against lateral displacement from said binding means and having a lateral lip extending over said switch lead and binding means.

In testimony whereof, I have signed my name to this specification, in the presence of two subscribing witnesses.

GEORGE A. BURNHAM.
